TYPOGRAPHICAL DISTRIBUTING APPARATUS FOR SLUG CASTING MACHINES

Julius F. Bettin, Bismarck, N. Dak.

Application June 3, 1940, Serial No. 338,645

6 Claims. (Cl. 199—34)

My invention relates to typographical distributing apparatus for slug casting machines, such as "Linotype" machines, Intertype machines, etc.

5 An important object of the invention is to provide a pi-matrices stacker device, which will receive and hold the sorts-matrices, against stacking or displacement and which will permit of the ready release of the pressure upon the column of sorts-matrices so that a selected sorts-matrix may be removed without removing adjacent sorts-matrices by contact therewith.

10 A further object of the invention is to provide yielding means to advance the resistant-block toward the sorts-matrices for properly holding them within the pi-matrices stacker and to automatically shift the resistant-block forwardly toward the star-wheel when sorts-matrix or sorts-matrices are removed whereby the group 15 of sorts-matrices are properly held, when the length of the group increases or decreases.

15 A further object of the invention is to provide releasable latch means to hold the resistant-block against movement toward the star-wheel, whereby pressure may be removed from the 20 group of sorts-matrices, when it is desired to remove a selected sorts-matrix.

25 Other objects and advantages of the invention will be apparent during the course of the following description.

30 In the accompanying drawing forming a part of this application and in which like numerals are employed to designate like parts throughout the same,

35 Figure 1 is a front elevation of my pi-matrices stacker device, showing the same applied to a "Linotype" machine,

40 Figure 2 is an enlarged central vertical longitudinal section through the sorts-matrices return tube and associated elements, parts being shown in elevation,

45 Figure 3 is a plan view of the pi-matrices stacker device, separated from the tube,

Figure 4 is a longitudinal section taken on line 4—4 of Figure 3,

Figure 5 is a transverse section taken on line 5—5 of Figure 3,

Figure 6 is a similar view taken on line 6—6 of Figure 3, and,

50 Figure 7 is an end elevation of a slightly modified form of latch-bar.

55 In the drawing, wherein for the purpose of illustration is shown a preferred embodiment of my invention A designates the ordinary magazine of a "Linotype" machine, in which is stored

the usual complement of matrices, and B is a return tube for the sorts-matrices. G is a pulley applied to one of the ordinary shafts of the "Linotype" machine and this pulley drives a belt F. The foregoing description is that of the 5 ordinary "Linotype" machine as shown in Letters Patent 630,112, issued to J. R. Rogers, under date of August 1, 1899. While the invention is shown as applied to one type of slug casting machine, such as a "Linotype" machine, it is not restricted 10 to this application, as it may be applied to any type of slug casting machine.

The numeral 18 designates the pi-matrices stacker as a whole, which is suitably secured to a stationary arm 11 and to a throat 12, formed 15 upon the lower end of the tube B. The pi-matrices stacker may be supported by any suitable means and is preferably arranged at the front of the machine, in proximity to the keyboard, so that the sorts-matrices may be removed 20 from the pi-matrices stacker by hand and delivered to the composing devices of the "Linotype" machine.

The pi-matrices stacker comprises a shelf or ledge 13 and a back 14. The numeral 15 is the 25 pi-matrix stop which is adjustably mounted upon the ledge 13 within the throat 12 and is clamped in the selected adjusted position by a set screw 16 engaging within a slot 17. One end of the group or row of the sorts-matrices is pressed 30 against the pi-matrix stop 15. Arranged within the throat 12 is a rotary star-wheel 18, mounted upon a rotary shaft 19 driven by a pulley 20, in turn driven by the belt F. The star-wheel 18 is shown as having four points and each point 35 is adapted to project radially slightly beyond the leading edge of the pi-matrix stop 15. The invention is not restricted to the use of a star-wheel having four points as a star-wheel having two points may be used, as shown in Patent 40 1,886,099, issued to J. H. Hilpman, November 1, 1932.

That side of the throat 12 and tube B toward the leading end of the pi-matrices stacker is formed open so that the sorts-matrices falling 45 down the return tube B will engage with the star-wheel 18 and be fed thereby into the pi-matrices stacker in an upright position to produce an assembled row.

I provide a combined guide and brake device, 50 comprising a gate 21, pivoted at 22 upon a stationary bracket 23. This gate has a weight 24 which swings the lower end of the gate into the bore of the tube B. The gate 21 serves to retain the thin sorts-matrices in the upright posi- 55

tion when traveling through the tube and to somewhat break the fall of the thicker and heavier sorts-matrices.

The numeral 25 designates a self-acting resistant-block, having a horizontal base 26 provided with a longitudinal groove 27, passing through its bottom. This groove receives the vertical arm 28 of a guide 29 having a lower horizontal arm 30. The vertical arm 28 operates within an elongated slot 31 while the horizontal arm 30 operates within a lower recess 32. The vertical arm of the guide is held within the slot 27 by a transverse pin 33. It is thus seen that the resistant-block or element 25 is mounted 15 to move longitudinally of the ledge 13 and is guided in such movement.

The vertical arm 28 is provided with a longitudinal opening or port 34, to receive one end of a flexible element, wire or cable 35, preferably having its free end knotted. This flexible element passes over a grooved pulley 36 carried by a shaft 37, arranged adjacent to the pi-matrix stop 15, as shown. The opposite end of the flexible element 35 passes over a guide-pulley 38, and is wound upon a drum 39 and has its opposite end attached to this drum. This drum 39, Figure 6, has a hub 40 and this hub is rigidly mounted upon a horizontal shaft 41. The shaft 41 is rotatable within openings 42 formed in plates 43 rigidly secured to the ledge 13 and depending therefrom. The space between the plates 43 is covered by a housing element 44, this element and the plates constituting a housing. The numeral 45 designates a spring-holding housing having openings or slots 46 within which the hub 40 is rotatably mounted. The housing 45 is held in place by a screw 47. Arranged within the housing 45 is a spring 48, one end of which is attached to the hub 40 and the opposite end of which is anchored to the housing 45, as shown at 49. The spring is tensioned to turn the hub 50 clockwise, in Figure 4. This clockwise movement of the drum 36 will cause the flexible element to wind upon the drum and hence shift the resistant-block or element 25 to the left, Figure 4.

Extending longitudinally of the ledge 13, adjacent to its free edge is a horizontal latch-bar 51, provided at its ends with trunnions or pivots 52 which are pivotally mounted in brackets 53 and 54, which are rigidly attached to the ledge 13. The latch-bar 51 is supported to turn upon its longitudinal axis and the trunnions 52 are nearer the inner edge of the latch-bar. The latch-bar is provided near its longitudinal center with ratchet teeth 55 which face toward the leading edge of the pi-matrices stacker or to the right, Figure 3. The latch-bar 51 is held in its normal transverse horizontal position by leaf-springs 56, engaging beneath the same and these leaf-springs are fixed to the ledge 13. The downward movement of the outer edge of the latch-bar 51 is limited by stops 57.

The invention is not limited to the use of leaf-springs for returning the latch-bar to the normal transverse horizontal position. In Figure 7, I have shown the latch-bar provided at its inner longitudinal edge with a weight 58 which returns the latch-bar to the normal transverse horizontal position. I may use either the spring or the weight.

A dog or pawl 59 extends transversely of the resistant-block and is arranged within a transverse slot 60 therein and is pivotally mounted to the base 26 as shown at 62. This dog is gravity operated and is provided at its free end with a

downwardly facing jaw 63, to engage with the ratchet teeth 55. The downward movement of the dog 59 is limited by contact with the ledge 13 and when the outer edge of the latch-bar 51 is depressed, the ratchet tooth 55 is moved out 5 of engagement with the jaw 63, and the spring will then shift the resistant-block or element 25 to the left, Figure 3.

The operation of the apparatus is as follows:

After the casting of the type, the ordinary 10 matrices are returned through the distributing mechanism to the magazine from which they started. The sorts-matrices are also returned through the distributing mechanism and are returned through the tube B to the pi-matrices 15 stacker device. As the matrix gravitates down the tube B it assumes a position in advance of the star-wheel 18 and when the star-wheel is turned the sorts-matrix is lowered and shifted to the right, Figure 2, moving the resistant-block 20 or element 25 to the right in opposition to the spring 48. The operation is repeated until all sorts-matrices are returned to the ledge 13. When the operator desires to use a selected sorts-matrix, he first shifts the resistant-block or element 25 to the right, for one or more teeth 55 and the dog 59 and the coacting tooth 55 will now hold the resistant-block or element out of contact with the end of the group of sorts-matrices. This will relieve the pressure between the several 30 sorts-matrices and the selected sorts-matrix may then be removed, and after this the operator may depress the outer edge of the latch-bar 51, conveniently adjacent to the point of removal of the sorts-matrix and this will release the resistant-block 25 and the spring will then automatically shift it to the left so that it will again engage the end of the group of sorts-matrices for holding the sorts-matrices in the group in the upright 35 position. As the star-wheel 18 continues to rotate, it will feed the sorts-matrices in succession into the pi-matrices stacker thus increasing the length of the group and shifting the resistant-block 25 to the right.

It is to be understood that the form of my invention herewith shown and described is to be taken as a preferred example of the same and that various changes in the shape, size, and arrangement of parts may be resorted to without departing from the spirit of my invention or the 50 scope of the subjoined claims.

Having thus described my invention, what I claim is:

1. In a typographical distributing apparatus, a pi-matrices stacker having a ledge, means to feed 55 sorts-matrices to the ledge so that the sorts-matrices will be supported on end by the ledge, a resistant element to apply pressure to the group of sorts-matrices, means to move the resistant element toward the group of sorts-matrices to 60 apply the pressure thereto, and releasable latch means to hold the resistant element against the action of the yielding means and including a member having a group of teeth extending longitudinally of the ledge and a coacting dog, the 65 member and dog being relatively movable for effecting a disengagement between the same.

2. In a typographical distributing apparatus, a pi-matrices stacker having a ledge, means to feed sorts-matrices to the ledge to form a group 70 thereon, a resistant element movable longitudinally of the ledge, yielding means to move the resistant element to apply pressure to the sorts-matrices, a member having a group of teeth extending longitudinally of the ledge, and a dog 75

connected with the resistant element for engaging the teeth.

5. 3. In a typographical distributing apparatus, a pi-matrices stacker having a ledge, means to feed sorts-matrices to the ledge to form a group thereon, a resistant element movable longitudinally of the ledge, yielding means to move the resistant element to apply pressure to the sorts-matrices, a group of teeth extending longitudinally of the pi-matrices stacker, a dog connected with the resistant element for engaging the teeth, the dog and group of teeth being relatively movable for effecting a disengagement between the same.
10. 4. In a typographical distributing apparatus, a pi-matrices stacker having a ledge, means to feed sorts-matrices to the ledge to form a group thereon, a resistant element movable longitudinally of the ledge, yielding means to move the resistant element in one direction to apply pressure to the sorts-matrices, a latch-bar extending longitudinally of the pi-matrices stacker and pivotally supported to turn upon its longitudinal axis and having a longitudinal group of teeth, 20 and a dog carried by the resistant element and arranged to engage the teeth.
15. 5. In a typographical distributing apparatus, a pi-matrices stacker having a ledge, means to feed sorts-matrices to the ledge to form a group

thereon, a resistant element movable longitudinally of the ledge, yielding means to automatically move the resistant element in one direction to apply pressure to the sorts-matrices, a latch-bar extending longitudinally of the pi-matrices 5 stacker and pivotally supported to turn upon its longitudinal axis, said latch-bar having a group of teeth upon its upper surface, a dog movably mounted upon the resistant element to engage the teeth, said dog having a limited downward 10 movement, the teeth disengaging the dog when the outer edge of the latch-bar is depressed, and means to return the latch-bar to the normal position after it is depressed and released.

6. In a typographical distributing apparatus, a 15 pi-matrices stacker having a ledge, said ledge having a stop, means to feed sorts-matrices to the ledge in advance of the stop to form a group of the same upon the ledge, a resistant element mounted upon the ledge to move longitudinally 20 thereof, a pulley, a flexible element secured to the resistant element and passed about the pulley, a rotary drum having the flexible element secured thereto and upon which the flexible element is wound, a spring to turn the drum in one direction, and releasable latch means for holding the resistant element against movement in opposition to the action of the spring. 25

JULIUS F. BETTIN.
